COMBINED WINDROWER AND CONDITIONER

William D. Long, Hesston, and Richard E. Ten Eyck,
Wichita, Kans., assignors to Hesston Manufacturing
Company, Inc., Hesston, Kans., a corporation of Kansas

Filed May 19, 1965, Ser. No. 85,356

Term of patent 14 years

(Cl. D40—1)

Des. 204,612

PAGE 2

FIGURE 1 is a front elevational view of a combined windrower and conditioner, showing our new design;

FIG. 2 is an elevational view showing one side thereof;

FIG. 3 is an elevational view showing the other side thereof;

FIG. 4 is a rear elevational view thereof; and

FIG. 5 is a front top perspective view showing our combined windrower and conditioner.

The dominant features of our design reside in the portions shown in full lines.

We claim:

The ornamental design for a combined windrower and conditioner, substantially as shown and described.
